UNITED STATES PATENT OFFICE

2,018,655

MERRY GO ROUND

Andrew Asikainen, Green Bay, Wis.

Application June 20, 1932, Serial No. 618,253

1 Claim. (Cl. 272—33)

The invention relates to an amusement apparatus, and more especially to a merry-go-round for children.

The primary object of the invention is the provision of an apparatus of this character, wherein the rotating table or platform is operated by the foot of a child or the feet of children when occupied, thereby eliminating the use of gearing and mechanical driving power, thus rendering the apparatus safe for use, the mounting of the table or platform being novel in form.

Another object of the invention is the provision of an apparatus of this character, wherein a large handwheel is located centrally of a turn-table or platform so that children mounting the latter can readily and easily grasp said wheel and by foot pressure upon the table or platform the latter will be rotated for a merry-go-round action thereby giving amusement and pleasure to the children.

A further object of the invention is the provision of an apparatus of this character, which is simple in construction, thoroughly reliable and efficient in operation, readily and easily driven, strong, durable, safe for use, lending attraction and amusement to the users, and inexpensive to manufacture and install.

With these and other objects in view the invention consists in the features of construction, combination and arrangement of parts as will be hereinafter more fully described, illustrated in the accompanying drawings, which disclose the preferred embodiment of the invention, and pointed out in the claim hereunto appended.

35 In the accompanying drawings:

Figure 1 is a top plan view of the apparatus constructed in accordance with the invention.

Figure 2 is a side elevation of the same.

40 Figure 3 is an enlarged fragmentary sectional view on the line 3—3 of Figure 1 looking in the direction of the arrows.

Figure 4 is a sectional view on the line 4—4 of Figure 3 looking in the direction of the arrows.

45 Similar reference characters indicate corresponding parts throughout the several views in the drawings.

Referring to the drawings in detail the apparatus comprises a base or bed A, preferably made from angle pieces 10, these being disposed at substantially right angles to each other and are joined to a center bearing 11 of any approved type. It is to be understood that this base or bed A may be otherwise formed so as to constitute a float, whereby the apparatus can be utilized in water, although the preferred construction of

the same is usable upon the ground. The bearing 11 is provided with a center hub 12 in which is keyed or splined at 13 the lower end of a stationary shaft 14 which rises perpendicularly above the base or bed A.

5 The shaft 14 is surrounded by a tubular column or post 15 which at its lower end has a cone like formation 16 and likewise the upper end of the hub 12 is formed with a cone 17 so that an anti-friction device 18 will be confined therebetween, and in this instance the device is in the nature of bearing balls.

The column or post immediately above the cone 16 is provided with a spider 19 to which are secured horizontally disposed radial sills 20, these 15 being formed with outwardly inclined upper edges 21. Upon the upper edges 21 of the sills 20 rest tread or floor boards 22, which are secured in place in any suitable manner and these with the sills constitute the turn-table or plat- 20 form of the apparatus.

The upper end of the shaft 14 has a reduced threaded terminal 23 to which is fitted the center hub 24 of a hand wheel 25, the latter being held by a nut 26 engaged on the reduced end 23.

25 Suitably mounted upon the turn-table or platform at equi-distances apart are double seats 27, these being adapted for occupants desiring to ride said table or platform.

The head-wheel 25 at its hub 24 telescopes over 30 the upper end of the column or post 15, while within the latter are bushings 28 and 29, respectively. The hub 24 is provided with a lubricant passage 30 for permitting oiling of the column which rotates on the shaft 14.

35 In the use of the apparatus a child or children mount the table or platform and grasp the wheel, then such child or children exert pressure in an angular direction by their feet upon the table or platform so as to cause the turning of the same at 40 variable speeds thus lending amusement and pleasure to those using the apparatus.

45 There are no projecting parts or gearing associated with the apparatus thus the same being rendered safe in the working thereof.

It is of course understood that the machine is operated by the feet of the child, children or adults, and this effected by holding onto the wheel 25 and with the feet the platform is turned, the faster the gait or stride on the latter the faster the machine revolves. By holding oneself in check by pulling the opposite way to the travel of the platform the wheel 25 acts as a brake and stops almost instantly but not abruptly the machine. The wheel 25 is station- 55

- ary and is fastened at the top of the shaft 14 which latter connects with the lower casting or base. This platform is supported by the upper or top casting which revolves around the shaft, 5 these castings being suitably fitted with anti-friction bearings, and thereby making it possible to operate the platform without much effort at all and thus lending amusement and pleasure to those using the machine.
- 10 10 What is claimed is:
- An apparatus of the kind described, comprising a body forming a base, a center bearing on the base and forming a hub rising above the latter, a vertical shaft splined in said hub and rising 15 from said base, a tubular column fitted over the shaft and having a cone-like lower end receiving

the upper portion of the hub, anti-friction means about the upper portion of the hub and within the cone-like lower end of the column, a spider formed with the column next to the cone-like end, a turn-table forming a platform supported by the spider, a hand wheel fixed to the shaft above the column high enough for persons to hold onto and propel the platform with their feet, seats on the platform at the outer edge thereof to be far enough away from the wheel to give the persons operating the latter ample space about said wheel to propel the platform and a maximum walking area between the wheel and seats and a central hub on the under side of the wheel and fitted over the upper end of the column. 10 15

ANDREW ASIKAINEN.
